UNITED STATES PATENT OFFICE

JOSEPH H. SIINO, OF PITTSBURG, CALIFORNIA

DOOR HOLDER

Application filed June 11, 1930. Serial No. 460,350.

This invention relates to door holders and has for its special object the provision of an auxiliary tool for carpenters' and cabinet makers' use whereby a hung door may be retained in a definite position while the door is being mortised for, and locks or latches fitted and installed.

Another object of the invention is to provide a device of the type described which is automatic in action, and which may be applied to doors of different thicknesses, without in any way marring the door, and which is instantly and conveniently attached and detached, and which will retain the door at any angle of opening to which the door is adjusted.

Other objects of the invention will become apparent as the following detailed description is read on the drawings forming a part of this specification.

The invention consists primarily of an inverted channel adapted to fit about the lower outer end of a door, the channel having hingedly connected and resiliently retracted transverse legs with resilient feet adapted to engage the floor on opposite sides of the door, the inward pull of the resilient members causing the feet to engage the floor and brace the door against swinging in either direction, thereby securely preventing movement thereof while mortising and similar operations are being performed.

The invention is adequately illustrated in the accompanying drawings in which:

Fig. 1 is a top plan view of the invention;

Fig. 2 is a front elevation thereof indicating its method of attachment to a door, and, in dotted lines, the retracted position of the legs;

Fig. 3 is a side elevation of the device as applied to a fragmentary section of a door.

Similar reference characters are used to designate similar parts throughout the several views.

The operation of the device is best indicated in Fig. 2 in which a door 4, an end view of the lower part of which is shown, has the channel shaped section 5 placed about the lower end. The legs 6 and 7 are hingedly connected between the ears 8 by means of

bolts 9 and have fixed to the lower end the resilient feet 10 which are adapted to engage the floor 11.

Springs 12 have the outer ends bent at right angles as at 13 and 14, the bent ends being retained respectively in apertures 15 in the legs 6 and 7 and 16 in the ears 17. The resilient feet 10 are retained by any convenient method and are indicated in the drawings as being cup shaped members retained on a circular foot 18.

The channel shaped section is preferably made to accommodate two or more thicknesses of doors and this is accomplished by forming this channel to a plurality of different widths as shown at 19 and 20.

The operation of the device is as follows: With the door partly open the legs 6 and 7 are drawn outwardly against the tension of the springs 12 and the channel shaped section placed about the front lower end of the door with the web 21 against the bottom of the door. The legs 6 and 7 are then released, and are automatically drawn inwardly until the web 21 is forced against the bottom of the door, the legs 6 and 7 assuming the position shown in full lines in Fig. 2, the feet 10 frictionally restraining the door from movement in either direction.

For removal it is simply necessary to spread the legs 6 and 7 when the device may be slipped off the door, the legs then automatically folding against the sides by action of the springs 12 as indicated in dotted lines in Fig. 2.

Having described an operative method of constructing and operating the device it will be understood that variations in construction and arrangement of parts which are consistent with the appended claims may be resorted to without departing from the spirit or scope of the invention or sacrificing any of the advantages thereof.

What I claim is:

1. A door holder adapted to retain a partly open door against movement in either direction, in combination, means adapted to freely fit about the bottom of the door and having pivotally mounted, resiliently retract-

ed members adapted to engage the floor on opposite sides of the door.

2. A door holder adapted to retain a partly open door against movement in either direction, comprising an inverted channel shaped member adapted to fit about the bottom and lower sides of a door, the legs of said channel having pivotally mounted thereon and resiliently retracted, oppositely disposed strut members, the lower ends of which are adapted to engage the floor when in angular relation to said door.

3. A door holder, in combination, a substantially channel shaped member in inverted position and having pivotally attached to and adjacent the upper edge of the legs, oppositely disposed, depending, resiliently retracted strut members, the ends of which extend below the web of said channel shaped section.

In testimony whereof I have affixed my signature.

JOSEPH H. SIINO.
